UNITED STATES PATENT OFFICE.

CHARLES E. KOONTZ, OF BALTIMORE, MARYLAND.

FIRE-ALARM APPARATUS.

Application filed March 3, 1923. Serial No. 622,614.

This invention relates to fire alarm boxes. The invention has for its chief characteristic the provision of means whereby the controlling element of the alarm mechanism is automatically actuated incident to the opening of the door of said alarm box, so that those who find it necessary to use the box will not fail to sound the alarm through excitement or forgetting, or through their lack of knowledge as to how the alarm should be sounded.

In carrying out the invention I provide a key controlled means for maintaining the mechanism in normal position to allow the door to be opened without sounding the alarm when it is necessary to inspect the mechanism or to open the door for any other purpose whatsoever.

The nature and advantages of the invention, will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

30 Figure 1 is a front elevation of the box, showing the normal position of the parts, the door of the box being partly broken away.

35 Figure 2 is a sectional view taken on the line 2—2 of Figure 1, looking in the direction of the arrows.

Figure 3 is a view showing the normal relation between the alarm control element and the pivoted arm for actuating said alarm.

40 Figure 4 is a detail view of the pivoted dog.

Figure 5 is a detail view of the keeper therefor.

45 Figure 6 is a view somewhat similar to Figure 1 showing the door opened and the arm maintaining the mechanism in normal position.

50 Figure 7 is a sectional view taken on the line 7—7 of Figure 6 looking in the direction of the arrows.

Figure 8 is an enlarged fragmentary front elevation, with the door opened showing the active position of the parts.

55 Referring to the drawings in detail, 10 indicates an alarm box which may be con-

structed from any suitable material and vary in size without departing from the spirit of the invention, the box being equipped with an inner door 11 and an outer door 12. The alarm mechanism, not shown, is concealed by the inner door 11, and includes the controlling element 13 which is mounted for pivotal movement, projecting through a slot or opening 14 in the inner door 11, so that it may be readily accessible subsequent to the opening of the front door. The outer door 12 is normally locked by a key actuated bolt in the usual well known manner, the key 15 being housed in a suitable casing 16 carried by the outer door 12, and which casing includes a glass panel 17. It is of course understood that the glass panel 17 must be first broken in order to gain access to the key 15 so that the door 75 may be unlocked, and subsequently opened. In order to sound the alarm, the controlling element, under ordinary circumstances must be depressed, however, this is frequently overlooked by the person finding it necessary 80 to use the box either because the said person is excitable or ignorant of the particular manner in which the alarm is operated. In order to eliminate any possibility of the alarm not being sounded under such circumstances, 85 I provide means whereby the controlling element 13 is automatically actuated incident to the opening of the outer door 12.

For this purpose I make use of a horizontally disposed lever 18 which is pivoted 90 at a point between its ends as at 19, upon one side of the inner door 11. One end of this lever is curved upwardly and is formed with a cam surface as at 20, for a purpose to be hereinafter described. The opposite end 95 of this lever is pivotally associated with a link 21 arranged substantially vertically and having its upper end pivotally associated with what I term a keeper having a dog to be hereinafter described. This keeper is indicated in Figure 5 at 22, and is formed with a bearing 23 for pivotal movement upon a screw bolt or pivot 24 projecting from the inner door 11. It is also provided with an opening 25 to accommodate the pivot 26 105 which associates it with the link 21. This keeper is bifurcated as at 27 and provides cam like surfaces which cooperate with the active extremity 28 of the pivoted dog shown in Figure 4. This dog is pivoted at one end 110 as at 29 upon an arm 30 which has one end pivoted as at 31 upon the inner door 11.

The arm 30 has its other end curved in the manner shown and the dog 32 illustrated in Figure 4 is pivoted on this curved extremity, projecting a slight distance above the latter and having its upper end offset as at 33. This offset extremity is connected with the adjacent end of a coiled spring 34, the other end of said spring being fixed to the door 11, so that after each operation of the mechanism, which takes place incident to the opening of the door 12, the said spring 34 returns the pivoted dog 32 to a position with relation to its keeper 22 so that these parts will automatically assume normal position when the lever 18 is depressed incident to the closing of the door. In other words, the mechanism operates to sound the alarm when the door is opened and is automatically reset for another operation when the door is swung to its closed position. The arm 30 is also provided with a stop lug 35 which limits the movements of the pivoted dog 32 in the direction of its keeper, while also projecting from this arm 30 is an additional lug 36 arranged immediately above the adjacent end of the alarm control element 13 contacting and depressing the latter when the lever 18 is moved downwardly under the influence of the spring 37. It will be noted that this spring has one end secured to the lever 18 and its other end secured to the door 11. The active extremity 28 of the pivoted dog 32 is normally received by the bifurcation 27 of the keeper shown in Figure 5, which is held in this position under the influence of the spring 34. Projecting from the inner face of the outer door 12 is a roller 38 having a tapered end and which cooperates with the cam surface 20 of the lever 18, so that when the door is closed the roller rides upon the upper edges of the curved extremity, and elevates the lever against the tension of the spring 37, thereby resetting the mechanism for a second operation.

In practice, when it is desired to sound the alarm, the glass panel 17 is broken so that access may be had to the key 15 which is turned to unlock the outer door 12 which swings open when released by the pressure of the lever 18 upon the roller 38 at which time the lever is swung on its pivot 19 under the influence of the spring 27, to the position illustrated in Figure 8. As the lever is moved in this direction, the keeper 22 is swung downwardly on its pivot, being directly connected with the link 21 associated with the lever 18. Consequently, the keeper forces the pivoted dog 32 downwardly, by reason of its association with the active extremity 28 thereof, but as this extremity 28 moves over a cam 39, it is obviously moved away from the keeper to allow the spring 34 to subsequently function for the purpose above mentioned. However, before the pivoted dog is thus separated from the keeper,

the downward movement of the dog depresses the pivoted arm 30, and as the lug 36 contacts the adjacent end of the alarm controlling element 13, it is quite apparent that this element 13 can also be depressed to actuate the alarm mechanism, just the same as if the element 13 was depressed manually. After the mechanism described has been operated for this purpose, the spring 34 moves the pivoted dog 32 to a position with relation to its keeper 22, so that when the lever 18 is again depressed by the roller 38 incident to the closing of the door, the parts will be automatically reset. The position of the dog 32 with relation to its keeper just prior to being reset as stated is clearly illustrated in Figure 8. In connection with the operation of the lever 18 by the roller 38, it is pointed out that upon closing of the door 12, the roller 38 engages the cam surface 20 formed on the lever 18 and draws the same to operative position, and this action resets the parts as will be apparent and as shown in Figure 1 of the drawing.

It is sometimes necessary to gain access to the interior of the box for the purpose of inspecting the alarm mechanism and also for the purpose of making repairs thereto and for various other reasons, at which time it is not desired to sound the alarm. Consequently I have provided means whereby the mechanism above described can be maintained in its normal position, while the outer door is opened, and also permit the inner door to be subsequently opened with said mechanism in such a position. The means for this purpose consists of a key actuated bolt 40 which operates in a suitable casing 41 secured to the inner door 11 and provided with a key hole slot 42. The outer door 12 is also provided with a key hole slot 43 normally covered by a pivoted plate 44. It will be noted that the key hole slot 43 of the outer door is arranged at a right angle to the key hole slot 42 above mentioned, so that after the key has been inserted, in the key hole slot 43 it must be subsequently turned to accommodate itself to the key hole slot 42, before the bolt 40 can be actuated. As this arrangement of the key hole slot is only known to inspectors or those authorized to open the box by means of the key, the arrangement prohibits unauthorized persons from tampering with or opening the box. In Figure 1, I have shown the normal position of the bolt 40, wherein the bolt projects beyond the lower edge of the casing 41, which position of the bolt permits the lever 18 to be freely operated in the manner above described. But, when it is desired to open the outer door without sounding the alarm, the bolt 40 is operated through the instrumentality of a key, not shown, to arrange the bolt in the position shown in Fig-

ure 6. This is done of course before the outer door is opened so that incident to the opening of the door 12, the lever 18 is supported in its normal position against the influence of the spring 37 to prevent sounding of the alarm. The inner door 11 can also be then opened to gain access to the alarm mechanism for any purpose whatsoever without disturbing the normal arrangement of the mechanism carried by the door 11.

Projecting from the inner side of the outer door 12 is a stud member including a fixed section 45 and a pivoted section 46, the latter being disposed in axial alignment with the section 45 when the door is opened. This stud member is employed to prevent the outer door from being closed without retracting or returning the bolt 40 to its normal position, which may be otherwise done inadvertently by the inspector or the person repairing the box. So that when the bolt 40 is in the position shown in Figure 6, the door 12 cannot be fully closed, inasmuch as the bolt 40 is in the path of movement of the tubular member which holds the door partly open. However, when the bolt 40 is retracted or returned to normal position and under ordinary circumstances when the door is swung to its closed position, the pivoted section 46 of this tubular member rides on the upper edge of the lever 18 assuming the position shown in Figure 2, so as not to interfere with the closing of the door.

The detail operation performed by the inspector of the box when it is desired not to sound an alarm, is described as follows: The key above mentioned is inserted in the key hole slot 33 and turned to be positioned in the key hole slot 42 for arranging the bolt 40 to operative position against the lever 18 so that the parts are retained in position as shown in Figure 6 of the drawings. The key is then removed from the lock and the door 12 opened. The door 11 can then be opened and closed without disturbing the parts, and when it is desired to return the bolt 40 to inactive position, the key is inserted in the key hole slot 42, but before the bolt is moved, the inspector must arrange the dog 32 so that it will rest upon the upper edge of the link 21 to prevent the dropping of the arm 30 on the control element 13. This position of the dog is shown in Figure 8 of the drawing, the bolt 40 can then be moved to inoperative position without fear of the arm 30 pressing the control element 13. When the bolt is thus moved, the lever 18 will drop under the influence of the spring 37 and be out of the path of the stud member, so that the door 12 can be readily closed to reset the parts as shown in Figure 1.

While it is believed that from the foregoing description, the nature and advan-

tages of the invention will be readily apparent, I desire to have it understood that I do not limit myself to what is herein shown and described and that such changes may be resorted to when desired as fall 70 within the scope of what is claimed.

Having thus described the invention, I claim:

1. A fire alarm box including an alarm control element, a door closing said box, means whereby the control element is actuated to sound the alarm incident to the opening of the door, means whereby the door may be opened without operating the control element and means carried by said door and arranged to engage a part of one of said means to prevent the closing of said door when the second mentioned means is disposed in operative position.

2. In an automatic alarm operating device 85 for fire alarm boxes, the combination with the inner and outer doors thereof and the alarm operating device, of a movable member secured to said inner door, means whereby said movable member may operate the 90 alarm operating device, means secured to said outer door and engaging said movable member to retain the latter in inoperative position when said outer door is fastened and disengaging said member when the 95 outer door is unfastened, a lock on said inner door which may be operated from the outer door and the bolt of which may be disposed against said movable member to hold it in 100 inoperative position independent of the retaining means on the outer door and means to prevent the closing of said outer door while said movable member is held in inoperative position by said bolt.

3. An attachment for a fire alarm box including an alarm control element, a door closing said box and a locking device for said door, comprising means for operating the control element, means for automatically operating the first means and simultaneously swinging the door to open position when the door is unlocked, said second means including means carried by said door for holding the second mentioned means inoperative while the door is locked.

4. A fire alarm box including an alarm control element, a door closing said box, means whereby the control element is actuated to sound the alarm incident to the opening of the door, means whereby the door may be opened without operating the control element and means carried by said door and arranged to engage a part of the first mentioned means to prevent the closing of said door when the second mentioned means 120 is disposed in operative position.

5. A fire alarm box including an alarm control element, a door closing said box, locking means for said door, means for actuating said element to sound the alarm when 130

the door is unlocked, said means including a substantially horizontally disposed pivoted lever normally held inactive when the door is closed, a normally inactive movable stop adapted to occupy a position to prevent movement of the lever, whereby the door may be opened without sounding the alarm, and a stud member including a fixed section extending inwardly from the door, a pivoted section secured to said fixed section and arranged with respect to said lever to engage the latter to prevent the closing of the door when the normally inactive movable stop is disposed in operative position to prevent movement of said lever.

6. A fire alarm including a control element, a door closing said box, means including a substantially horizontally disposed spring actuated pivoted lever having a cam surface on a curved free end thereof, a substantially vertically disposed lever pivoted to the substantially horizontally disposed

lever, a pivoted bifurcated keeper pivotally receiving the upper end of the substantially vertically disposed lever, a spring actuated dog associated with the bifurcated portion of said keeper, a pivoted arm pivotally receiving the dog whereby said dog is adapted to actuate said arm, a lug on said arm and disposed adjacent the alarm control element, a roller on said door adapted to actuate the substantially horizontal lever to hold said parts of said means in normal position when the door is disposed in its closed position, said parts being rendered operative when the door is opened to allow the lug of the arm to actuate the alarm control element and said parts being again disposed to normal position by the engagement of the roller with the curved surface of the substantially horizontally disposed bar when the door is disposed to closed position.

In testimony whereof I affix my signature.

CHARLES E. KOONTZ.
